UNITED STATES PATENT OFFICE.

ABRAHAM G. JENNINGS, OF BROOKLYN, NEW YORK, ASSIGNOR TO
ABRAHAM G. JENNINGS & SONS, OF SAME PLACE.

DESIGN FOR A PARASOL-COVERING.

SPECIFICATION forming part of Design No. 16,055, dated April 21, 1885.

Application filed December 18, 1884. Term of patent 14 years.

To all whom it may concern:

Be it known that I, ABRAHAM G. JENNINGS, a resident of Brooklyn, in the county of Kings and State of New York, have invented and 5 produced a new and original Design for Parasol-Coverings, of which the following is a full description, in connection with the accompanying photographs.

In the accompanying photographs, Figure 10 1 is a perspective view of my new design for a parasol-covering. Fig. 2 is an enlarged photograph of a portion of said covering.

This invention relates to the new configuration of a covering for parasols; and it consists 15 of reticulated body A, having irregular four-sided meshes and the peculiar form shown in the accompanying photographs. At the edge the same may be provided with a suitable lace

border or fringe B. The white matter of the photographs shows the body of the parasol, 20 which is visible through the meshes of my new covering.

I claim—

1. The design for a parasol-covering, the same consisting of the reticulated body A, having 25 irregular four-sided meshes and the peculiar form substantially as shown.

2. The design for a parasol-covering, the same consisting of the reticulated body A, having 30 irregular four-sided meshes, and the peculiar form shown, and of the lace border or fringe B, substantially as shown.

ABRAHAM G. JENNINGS.
